UNITED STATES PATENT OFFICE.

EDMUND HINTZ, OF CHICAGO, ILLINOIS.

ADJUSTABLE FRAME.

Application filed March 23, 1922. Serial No. 546,053.

To all whom it may concern:

Be it known that I, EDMUND HINTZ, a citizen of Poland, residing at Chicago, in the county of Cook and State of Illinois, have invented certain new and useful Improvements in Adjustable Frames, of which the following is a specification.

This invention relates to certain new and useful improvements in adjustable frames, particularly adapted for being adjusted in size to accommodate picture, mirrors or the like of various sizes.

The primary object of the invention is to provide a very simple and durable form of adjustable frame of the above size wherein the natural mechanical construction of the device provides an ornamental appearance and means for obtaining a practical change in the size of the frame in an expeditious and simple manner.

Another object of the invention is to provide efficient means for maintaining the desired adjustment of the frame.

With the above general objects in view and others that will appear as the nature of the invention is better understood, the same consists of the novel form, combination and arrangement of parts hereinafter more fully described, shown in the accompanying drawing and claimed.

In the drawing, wherein like reference characters designate corresponding parts throughout the several views,

Figure 1 is a front elevational view of an adjustable frame constructed in accordance with the present invention,

Figure 2 is a side or edge elevational view of the device shown in Fig. 1;

Figure 3 is an enlarged sectional view taken on line III—III of Fig. 1, and

Figure 4 is a perspective view of one of the members employed for receiving securing bolts to maintain the frame in adjusted condition.

Referring more in detail to the several views, the present invention embodies an open substantially rectangular frame composed of a pair of side frame members 5, a top frame member 6 and a bottom frame member 7, each of which is of lazy tong construction involving a series of pivotally connected cross strips 8 whose pivots are indicated by the reference numeral 9. The adjacent ends of the side, top and bottom members 5, 6 and 7 are pivotally connected by oblique corner strips 10 which are pivotally

attached at each end at two points denoted by the numeral 11 to the adjacent end of the adjacent lazy tong frame member. A substantially rectangular frame involving effectively connected side, top and bottom frame members, is thus provided, and ornamentation may be provided by means of the ornamental corner members 12 rigidly secured to the oblique strips 10 between the adjacent ends of the frame members and extending transversely of said strip 10 as shown. The ornaments 12 may each comprise three substantially parallel strips of a desired configuration rigidly secured in spaced relation by transverse braces or cross bars 13, the outer ends of these strips being pointed and the two outside strips being of the same length, while the intermediate strip is the longer to give a rectangular appearance. It will be obvious that by forcing the two side frame members toward each other the width of the frame may be varied within convenient limits while a similar movement of the top and bottom frame members will lessen the length of the frame. On the other hand separation of these frame members will enlarge the frame as is obvious.

In order to maintain the frame in a desired adjusted size, an angle iron 14 is employed at each corner of the frame and comprises a central portion rigidly fastened to one of the corner oblique strips 10 with opposite legs 15 extending at an obtuse angle to the intermediate portion of the angle iron and provided with a longitudinal elongated slot 16. The next to the last pivot member at each end of each of the lazy tong frame members is in the form of a bolt 17 having a wing nut 18 threaded thereon and freely extending through the slot in the adjacent arm of the adjacent angle iron, whereby upon tightening of the wing nut, the lazy tong frame members will be maintained in adjusted condition to provide for retention of the frame in the desired size. Thus, by the loosening of eight wing nuts, two at each corner of the frame, the frame may be changed in size and when placed in the desired condition, may be so maintained by again tightening said wing nuts, the resultant structure being quite rigid and presenting a unique and ornamental appearance. Spaced a suitable distance apart upon the back wall of the frame are picture retaining clips 19.

From the foregoing description it is be-

lieved that the construction and operation as well as the advantages of the present invention will be readily understood and appreciated by those skilled in the art.

5 Minor changes may be made in the invention without departing from the spirit and scope of the invention as claimed.

What I claim as new:

An adjustable frame of the class described comprising a pair of side members, a top and a bottom frame member, said frame members being all of lazy tong construction and pivotally connected in end to end relation to provide an open substantially rectangular frame, the said frame having picture retaining clips thereon means associated with said frame members to hold the same against extending or collapsing, the connections between the ends of said frame members com-

prising oblique strips pivotally connected at 20 a plurality of points at each end to the adjacent ends of each adjacent frame member, and said means for maintaining the frame members against accidental extension or collapsing involving angle irons rigidly fastened to the oblique frame member connecting strips and having arms at opposite ends extending at an obtuse angle and provided with longitudinal elongated slots, said frame members involving pivot members near each 25 end thereof in the nature of bolts with wing nuts thereon, said bolts extending through the elongated slots of the angle iron arms, whereby tightening of the wing nuts will bind the parts to prevent the collapsing or 30 extension of the frame members.

In testimony whereof I affix my signature.

EDMUND HINTZ.
